(21) Appl. No.: **29/128,775**

The ornamental design for an optical monitoring window
having six wear resistant posts, as shown and described.

(22) Filed: **Aug. 31, 2000**

DESCRIPTION

(51) LOC (7) Cl. **16-99**

FIG. 1 is front and side perspective view of an optical
window having six wear resistant posts showing my new
design;

(52) U.S. Cl. **D16/130; D16/135**

FIG. 2 is a front view thereof, the rear view being of
identical appearance;

(58) Field of Search D16/130, 134,
D16/135, 136, 137; 359/356, 362, 504,
699, 744, 831, 894, 368, 642, 793, 804,
869

FIG. 3 is a top view thereof;

(56) **References Cited**

FIG. 4 is a bottom view thereof;

U.S. PATENT DOCUMENTS

FIG. 5 is a side view thereof, the opposite side being of
identical appearance; and,

D. 307,758 * 5/1990 Tsuji D16/135
D. 322,447 * 12/1991 Feinblloom D16/132
D. 334,940 * 4/1993 Wolinsky D16/134
D. 355,663 * 2/1995 Van Cort D16/130
D. 388,448 * 12/1997 Lonnstedt D16/135
D. 390,242 * 2/1998 Selden D16/135
2,312,542 * 3/1943 Goodman 359/894

FIG. 6 is a front view of an alternative embodiment of the
optical window of the present invention wherein the said
posts are of narrower diameter than the posts in the embodi-
ment of FIG. 2.
